 Inc., Middleton, Wis., a corporation of Wisconsin
 Filed Aug. 6, 1965, Ser. No. 477,848
 9 Claims. (Cl. 16—94)

ABSTRACT OF THE DISCLOSURE

First and second rod sections each having a rearwardly opening front passageway and a rear passageway spaced therefrom. Each section having a top wall with a rear portion disposed below the level of the front portion and a pair of forwardly facing rails on the top of the rear portion. A splice having a pair of rearwardly facing rails for engaging the rails on the rod sections and clamping means for holding the rod sections abutted. Bracket means similarly arranged as the splice for engaging the rails and mounting the rod.

This invention relates to improvements in supports for draperies, curtains, tapestries and the like.

For convenience, the improved support of the present invention is herein sometimes referred to as a drapery support; however, this is done by way of illustration and it should be understood that the support may be used with any type of drapery, curtain, tapestry, or other similar flexible hanging.

An object of this invention is to provide an improved drapery support, including at least two elongate rod sections, each having a pair of rails on the top side thereof and a splice member engaged with the rails for holding the two rod sections aligned and abutted end-to-end.

Another object is to provide a drapery support in accordance with the foregoing object and including a front passageway adapted for mounting generally contiguous to a ceiling and having rails and a splice member disposed behind the front passageway and generally hidden thereby.

It is another object of this invention to provide an improved drapery support including an elongate rod having a pair of rails on the top side thereof and brackets engaged with the rails for mounting on a supporting surface.

It is still another object to provide a drapery support in accordance with the foregoing object in which the brackets are disposed behind the front passageway and generally hidden thereby.

Other objects are to provide an improved drapery support which is attractive, which has a minimum depth, which may be mounted on either a ceiling or a vertical surface, which can be easily installed, and which can be readily and economically manufactured.

These, together with other objects and advantages of the invention will be more readily appreciated as the same becomes better understood by reference to the following detailed description when taken in accordance with the accompanying drawings wherein:

FIG. 1 is a perspective view of an embodiment of this invention;

FIG. 2 is a sectional view taken generally on line 2—2 of FIG. 1;

FIG. 3 is a sectional view taken generally on line 3—3 of FIG. 1;

FIG. 4 is a bottom view taken generally along line 4—4 of FIG. 3; and

FIG. 5 is a sectional view taken generally along line 5—5 of FIG. 1.

Reference is now made more particularly to the drawings, wherein similar reference characters designate corresponding parts throughout the several views. In general, the drapery support includes an elongate rod section, generally designated by the numeral 10, elongate end rod sections 12 and 14, splice members 16 and 16', and brackets which may take different forms as will hereinafter be described. Elongate rod section 10 includes a generally upright front wall or front face 20 and a top wall 22 attached generally at the upper end of the front face, as seen in FIG. 5. In its preferred form, elongate rod section 10 has a rearwardly extending bottom wall 24 attached to the lower end of the front face and an upwardly extending flange 26 attached to the rear end of the bottom wall. Preferably, the top wall 22 has a front portion 23 having a width approximating the width of the bottom wall 24 and a downwardly extending flange 27 attached to the rear side thereof. The front wall 20, bottom wall 24, front portion 23, and flanges 26 and 27 define a front passageway extending generally the full length of rod section 10. Flanges 26 and 27 have their adjacent edges 26a, 27a spaced apart to provide a rearwardly opening access to the passageway. Top wall 22 has a rear portion 28 attached to flange 27 and extending rearwardly therefrom. Rear portion 28 has a pair of rails 30 and 32 attached thereto and extending upwardly therefrom. Rail 30 has an upwardly extending leg 30a and a forwardly extending flange 30b attached adjacent the upper end of the leg. Similarly, rail 32 has an upwardly extending leg 32a and a forwardly extending flange 32b.

Elongate end rod sections or members 12 and 14, in the preferred embodiment, have a front wall and top and bottom walls having a generally equal cross section 35 with the walls of elongate rod section 10 and thereby define a front passageway extending generally the full length of rod sections 12 and 14. Likewise, rod sections 12 and 14 have a pair of rails attached to the rear portion of their top walls and these rails have a generally equal cross section with rails 30 and 32 of elongate rod section 10. Similar parts are, therefore, designated by the same number followed by the postscript prime ('), as seen in FIGS. 2 and 3.

In the embodiment illustrated, elongate rod section 10 conveniently has a second passageway disposed behind the above described front passageway and spaced a distance behind the rearwardly opening slot between flanges 26 and 27. As best shown in FIG. 5, the rear passageway of elongate rod section 10 is defined by a wall 34 depending from the rear portion 28 of top wall 22, a generally horizontal member 35 extending rearwardly from the lower end of wall 34, and rear wall portions 36 and 37 attached to rear portion 28 of top wall 22 and horizontal member 35, respectively. Said rear wall portions 36 and 37 have their respective edges 36a and 37a spaced apart to define a longitudinal slot extending substantially the full length of the elongate rod section 10. In the dual passageway construction illustrated, it is contemplated that a plurality of carriers 40 and master carriers 42 and 42' may be carried in the above described front passageway, as seen in FIG. 1, and slide gates or stops 46 may be removably mounted at the ends of the front passageway to retain the carriers in the passageway.

When used as a traverse rod, it is contemplated that draw cords 44 and 44' may be carried inside the rear passageway as shown in FIG. 5, and the longitudinal slot in the rear wall provides a convenient means for insertion of the cords into the rear passageway. To effectuate use as a traverse rod, elongate end member or rod 12 is shaped to provide a pulley housing for cords 44 and 44'. In the embodiment illustrated in FIGS. 2 and 3, end rod

section 12 has a pair of generally parallel depending walls 50 and 51 which are preferably aligned with walls 34 and 36, respectively, to provide a continuation of the rear passageway in rod section 10. Disposed between walls 50 and 51 are a pair of pulleys 52 and 53, as best shown in FIG. 2. It is contemplated that, in some uses, only one pulley may be required and may be disposed inside the rear passageway of elongate rod section 10 or in a separate end section such as rod section 12 or 14. End rod section 14 may have a cross section similar to that of elongate rod section 10 or may be an other-hand embodiment of end rod section 12. It is also contemplated that the draw cords 44 and 44' may be disposed at the opposite end of the drapery support, if desired, and in that situation the right hand end section would be a pulley housing similar to that described above for the pulley housing of section 12.

For use of the rod as a traverse rod, it is necessary that end rod 12 be mounted adjacent elongate rod 10 with the front passageways substantially aligned and with the pulley housing generally aligned with the rear passageway of rod 10. For this purpose, the aforescribed rails 30 and 32 on section 10 are arranged for alignment with rails 30' and 32' on end rod section 12. Splice member 16 is arranged to engage these rails and hold them in substantial alignment whereby the passageways are substantially aligned. This is accomplished by a pair of rail engaging means 56 and 58 on splice 16, as best shown in FIG. 3. Rail engaging means 56 includes a downwardly extending leg 56a and a rearwardly extending flange 56b. Similarly, rail engaging means 58 includes leg 58a and flange 58b. A clamping means is mounted in groove 63 to hold the rail engaging means engaged to the respective rails and, as shown, includes a clamp 60 and fastener 62. It is contemplated that one such clamping means may be utilized to clamp the splice onto both rod sections, however, the embodiment illustrated is conveniently in the form of a separate clamping means for the respective rod sections, such as 10 and 12, as shown in FIG. 4. It is also contemplated that one fastener may be utilized for the respective rod section, however the splice is best accomplished by a pair of fasteners on each clamp to more positively secure the sections abutted end-to-end and in alignment. The clamping means is of a particularly advantageous construction and, as shown in FIG. 4, has an opening therein, preferably formed with a semicircular portion 64 adjacent groove 63 in the splice and a larger opening portion 66, larger than the head of fastener 62, for passage of said head. It can be seen that the semicircular portion 64 is closely adjacent the shaft of fastener 62 and the fastener 62 engages a shoulder 65 defined by the edge of opening 66 adjacent the semi-circular portion 64. In this manner, the clamp 60 may be inserted into groove 63 after the fastener is screwed into splice 16 and thereafter the fastener may be securely tightened against the shoulder. This particular construction allows the clamp 60 to pivot about a point in groove 63 and effectively swing out of position as shown in phantom in FIG. 3. Thus, either section 10 or 12 can be removed from the splice without completely removing the clamping means or the clamping means can be loosened to allow longitudinal movement of the sections.

As stated above, the bracket means may take different forms. By way of example, it may be in the form of a wall bracket 70, shown in section in FIG. 2, or a ceiling bracket 72, shown in section in FIG. 5. Both wall bracket 70 and ceiling bracket 72 have a pair of rail engaging means including downwardly extending legs and rearwardly extending flanges similar to those described above for the splice 16 and the similar parts are illustrated with the same numbers followed by a prime ('). Also, both the ceiling bracket and wall bracket have a clamping means mounted in a groove 63' and the clamping means includes a clamp and a fastener similar to the clamp and

fastener described for the splice and similar parts are designated by the same numbers followed by the postscript prime ('). It is contemplated that the clamping means for the brackets need have only one fastener 62' and, consequently, only one opening 64' and 66' need be provided. Ceiling bracket 72 has an opening 74 therein for passage of a fastener 76 for mounting the bracket means on a horizontally disposed surface, such as ceiling 82. Wall bracket 70 includes a vertically disposed leg member 78 having openings 79 therein, through which may pass fasteners 76 for mounting the bracket means on a horizontally disposed surface, such as wall 84.

It should be noted that, because of the advantageous construction of the rod sections 10, 12, and 14, the brackets 70 and 72 and splice means are disposed behind the front passageway and are substantially hidden thereby. As a result, an attractive front face is all that is visible when the drapery support is mounted. This is particularly advantageous with the ceiling bracket 72 since the top of the front portion 23 of the top wall 22 is substantially in the same plane as the top of bracket 72 or splice 16. Thus, the front passageway is mounted closely adjacent the ceiling when the elongate rod is engaged with the ceiling mounted bracket 72. It is contemplated that the elongate rod section 10 may be utilized alone or that the brackets may be used to mount several lengths of rod spliced together, as by splice 16. The splice 16 conveniently has a plurality of holes 81 therein, as shown in FIG. 1, which allows the splice 16 to be utilized as a ceiling mount or bracket, if desired.

It is now deemed obvious that the present invention provides a particularly advantageous and attractive drapery support where two or more rod sections or members may be joined by a splice that is concealed behind the face and front passageway of the rod and where mounting brackets are similarly concealed. It can also be seen that the splice aligns the rods being joined to form a smooth front face and substantially aligned passageways and that the front passageway may be mounted closely adjacent to a ceiling surface.

While we have thus described a preferred embodiment of our invention, this has been done by way of illustration and not limitation, and we do not wish to be limited except as required by the appended claims.

45 We claim:

1. A support for draperies and the like comprising first and second endwise abutting rod sections having matching front faces and top walls extending rearwardly from said front faces, each rod section having spaced forward and 50 rear rails extending substantially the full length of said top walls, each rail including an upwardly extending leg integral with the respective top wall and a forwardly extending flange adjacent the upper end thereof, splice means for holding the first and second rod sections in said 55 abutted relationship and comprising an elongate body overlying the top walls of said first and second rod sections at the abutted ends thereof, forward and rear rail engaging means spaced a distance generally equal to the spacing of said forward and rear rails and extending generally the 60 full length of the body, each rail engaging means including a downwardly extending leg attached to the body and a rearwardly extending flange adjacent the lower end thereof, first and second clamping means on the body engageable with the top walls adjacent the rear edges thereof for urging the respective first and second rod sections forwardly with their rails engaging the rail engaging means.

2. A support for draperies and the like comprising first and second elongate rod sections each having means defining a passageway extending generally the full length 70 thereof, said means including a top wall having a front portion overlying the passageway and a rear portion disposed at a level below the top of the passageway and extending rearwardly therefrom, a splice means for holding the first and second rod sections abutted end to end

and with their passageways generally aligned, said splice means overlying only said rear portion of the top wall and having an upper surface disposed at a level approximating the upper level of said front portion of said top wall, rail means on the rear portion of the top wall for engaging the splice means, and clamping means on the splice means for engaging said rear portion of the top wall adjacent the rear edge thereof for holding the first and second rod sections with their rail means engaged to the splice means.

3. A support for draperies and the like comprising first and second elongate rod sections each having means defining a passageway extending generally the full length thereof and adapted for mounting adjacent a horizontally disposed surface, said means including a top wall having a front portion overlying the passageway and a rear portion disposed at a level below the top of the passageway and extending rearwardly therefrom, forward and rear generally parallel rails extending substantially the full length of each rod section, each rail including an upwardly extending leg attached to said rear portion of the top wall and a forwardly extending flange attached adjacent the upper end of the leg, each forwardly extending flange having its upper extremity at a level below the upper lever of the front portion of the top wall, splice means for holding the first and second rod sections abutted end to end and with their passageways aligned, the splice means including a body disposed behind the passageway of each rod section and extending over only the rear portion of the top wall, said body having a generally flat upper surface disposed at a level approximating the upper level of said front portion of the top wall and adapted for mounting adjacent the horizontally disposed surface, said splice means including first and second rail engaging means spaced a distance generally equal to the spacing of the first and second rails and extending generally the full length of the body, each rail engaging means including a downwardly extending leg attached to the body and a rearwardly extending flange attached adjacent the lower end of the leg, and the splice means including first and second clamping means on the body for holding the respective first and second rod sections with their rails contiguous to the rail engaging means.

4. A support for draperies and the like comprising first and second elongate rod sections abutted end to end and adapted for mounting adjacent a horizontally disposed surface, each rod section having a front passageway defined by a generally upright front wall and top and bottom walls attached thereto, the bottom wall having an upwardly extending flange portion, the top wall having a front portion and a downwardly extending flange portion attached thereto, said flange portions spaced from each other to define a rearwardly opening slot providing access to the front passageway, the top wall of each rod section having a rear portion attached to the downwardly extending flange portion and extending rearwardly therefrom at a level below the front portion, and a pair of parallel wall means attached to said rear portion and depending therefrom, said parallel wall means being spaced rearwardly from said slot and extending generally the full length of each rod section to define a rear passageway, at least one of said rod sections having at least one pulley rotatably supported between the parallel wall means, said rear portion of each top wall having first and second generally parallel rails extending generally the full length thereof, each rail including an upwardly extending leg attached to said member and a forwardly extending flange attached adjacent the upper end of the leg, splice means for holding the rod sections in said abutted relationship and with the passageways generally aligned, the splice means including a body disposed rearwardly of the front passageway and having an upper surface at a level approximating the top of said front portion of the top wall, first and second rail engaging means spaced a distance generally equal to the spacing of the first and second rails, and each including a downwardly extending

leg attached to the body and a rearwardly extending flange attached adjacent the lower end of the leg, and clamping means on the body for holding the first and second rod sections with their rails contiguous to the rail engaging means.

5. A support for draperies and the like comprising a first elongate rod section having a front passageway defined by a generally upright front wall and top and bottom walls attached thereto, the bottom wall having an upwardly extending flange portion and the top wall having a front portion and a downwardly extending flange portion attached thereto, said flange portions spaced from each other to define a rearwardly opening slot providing access to the front passageway, the top wall having a rear portion attached to the downwardly extending flange portion and extending rearwardly therefrom at a level below the front portion, a pair of parallel wall means attached to said rear portion and depending therefrom, said parallel wall means being spaced rearwardly from said slot and extending generally the full length of the rod section to define a rear passageway, first and second parallel rails mounted on the top of said rear portion and extending generally the full length thereof, each rail including an upwardly extending leg and a forwardly extending flange attached to the upper end of the leg;

a second elongate rod section having a front passageway defined by front, top and bottom walls having a cross section generally identical with the walls of the first rod, the top wall having a downwardly extending flange portion, and a rear portion attached thereto and extending rearwardly therefrom at a level below the front portion, a pair of parallel wall means attached to said member and depending therefrom and having at least one pulley rotatably mounted therebetween, and first and second parallel rails mounted on the top of said member and having a cross section generally identical with the rails of the first rod section;

splice means for holding the rod sections abutted end to end with their front passageways and first and second rails aligned, the splice means including a body disposed rearwardly of the front passageway and having an upper surface at a level approximating the top of the front portion of said top wall of each rod, first and second rail engaging means spaced a distance generally equal to the spacing of the first and second rails and each including a downwardly extending leg attached to the body and a rearwardly extending flange attached to the lower end of the leg, first and second clamping means on the body for holding the respective first and second rod sections with their rails contiguous to the rail engaging means; and

bracket means for mounting at least one of said rod sections on a supporting surface and having a generally horizontally disposed body having first and second rail engaging means having a cross section generally identical with the first and second rail engaging means on the splice means, clamping means for holding the rail engaging means contiguous to the rails of at least one of said rod sections, and fastening means for securing the bracket to the supporting surface.

6. A support for draperies and the like comprising an elongate rod disposed generally horizontally and bracket means for mounting said rod on a supporting surface, said rod having a front face and a top wall disposed rearwardly thereof, first and second rails spaced from each other and extending generally the full length of the rod, each rail including an upwardly extending leg attached to the top wall and a forwardly extending flange attached to the upper end of the leg, said bracket means including a generally horizontally disposed body having first and second

rail engaging means spaced a distance generally equal to the spacing of said first and second rails, each rail engaging means including a downwardly extending leg and a rearwardly extending flange attached to the lower end of the leg, and clamping means on the body for holding the rail engaging means contiguous to the rails whereby the rod is supported by the bracket means.

7. A support for draperies and the like comprising an elongate rod disposed generally horizontally, and bracket means for mounting said rod on a supporting surface, said rod having a front face and a top wall disposed rearwardly thereof, first and second rails spaced from each other and extending generally the full length of the rod, each rail including an upwardly extending leg attached to the top wall and a forwardly extending flange attached to the upper end of the leg, said bracket means including a generally horizontally disposed body having first and second rail engaging means spaced a distance generally equal to the spacing of said first and second rails, each rail engaging means including a downwardly extending leg and a rearwardly extending flange attached to the lower end of the leg, said body extending rearwardly past the rear edge of said top wall of the rod, and having a forwardly facing groove in its lower side and rearwardly of the rear of the top wall, a clamping member mounted in said groove and extending forwardly therefrom for engaging the top wall adjacent its rear edge, and fastening means for holding said clamping member contiguous to the top wall and thereby urging the rod forwardly with the rails engaging the rail engaging means.

8. The combination of claim 7 wherein said fastening means comprises a threaded shaft and a head larger than the shaft and attached thereto, and wherein said clamping member has an opening therein including a first portion for passage of said head and a semi-circular portion extending therefrom on the side adjacent said groove for passage of said shaft, said first portion defining a head engaging shoulder adjacent said semicircular portion said

shoulder located from the rear edge of the clamping member a distance approximating the distance from the back of said groove to the center of the threaded shaft, said fastening means and clamping member so arranged that the clamping member may be inserted into said groove after the fastening means is started and the head thereafter tightened against said shoulder.

9. A support for draperies and the like comprising an elongate rod disposed generally horizontally and having a front wall and a top wall extending rearwardly from the upper end of the front wall, said top wall including a front portion and a rear portion disposed at a level below said front portion, front and rear generally parallel rails extending substantially the full length of the rod, each rail including an upwardly extending leg attached to the rear portion of the top wall and a forwardly extending flange at the upper end of the leg, each said flange having its upper surface at a level below the upper level of the front portion of the top wall; and bracket means for mounting said rod on a supporting surface and including a body portion having a front end disposed rearwardly of the front portion of the top wall and an upper surface at a level approximating the upper level of said front portion, engaging means on the underside of said body portion for engaging each said front and rear rail, and clamping means mounted on the body for holding said engaging means contiguous to the rails whereby the rod is supported by the bracket means.
